UNITED STATES PATENT OFFICE.

ALFRED G. F. KUROWSKI, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,018,915.

Specification of Letters Patent. Patented Feb. 27, 1912.

Application filed October 4, 1910. Serial No. 585,185.

To all whom it may concern:

Be it known that I, ALFRED G. F. KUROWSKI, a citizen of the United States, residing in borough of Brooklyn, city of New York, in the county of Kings and State of New York, have invented certain new and useful Improvements in Type-Writing Machines, of which the following is a specification.

10 This invention relates to mechanisms of typewriting machines which regulate the width of the side margin on a sheet by ringing a bell and locking the keys when the carriage reaches a predetermined point.

15 One object is to improve and simplify these devices whereby a strong and unyielding lock is provided, the mechanism being readily applicable to existing machines, without necessitating careful or accurate 20 adjustment, and easily accessible for repairs, if necessary.

The usual pendent arm operated by the carriage of an Underwood writing machine, is, according to the present improvements, 25 connected by a link to a rock shaft on which is a finger or cam. Said finger thrusts a stop into the path of the universal bar which is operated at each type stroke, thereby blocking the type bars and keys. By turning 30 a button, the link is cast off to release the type keys.

In the accompanying drawings, Figure 1 is a perspective of the invention. Fig. 2 is a sectional view from front to rear of an 35 Underwood machine, showing the type bars locked. Fig. 3 is a detail of the stop seated in the frame. Fig. 4 is a detail side view of the mechanism when idle. Fig. 5 shows the mechanism released by the button after having 40 locked the type bars. Fig. 6 is a detail view of the operating tappets and cam.

Depressing any of a series of keys 1 on key levers 2, rocks an angle lever 2^a to swing one of the type bars 3 to cause types 4 on 45 said bars to strike a platen 5 mounted in a carriage 6. The carriage travels on front and rear rails 7, 8 of a framework 9, and is driven in the usual manner by a spring, (not shown,) its feed being controlled by an escapement mechanism including a vibratory frame 10, carrying a universal bar 11. As each type bar approaches the platen, it first strikes the universal bar to trip the escapement (Fig. 2).

55 The width of the right hand side margin

on the work sheet is controlled by the engagement of a cam or tappet 12 on the carriage with a bell-ringing and line-locking cam 13 on a slide 15, the latter adjustable along a rod 16 parallel with the direction of travel of the carriage, and held by a tooth 17 meshing with a rack 18. The slide rests partly upon said rack 18, which is journaled by arms 18^a preferably on the rod 16, and has a pendent arm 19, which is swung when 60 the tappet 12 strikes cam 13. As the foregoing mechanism is about the same as is disclosed in United States Patent to Wagner, No. 559,345, further illustration and description is omitted.

The swinging arm 19 is connected by a rearwardly extending link 20 to a crank 22 on a rock shaft 23 journaled in the frame 9. The joint of the link and arm is marked 21. The contact of the tappet 12 with the cam 70 13 forces the latter downwardly, the rack 18 yielding under the weight of the carriage, and the arm 19 swinging forwardly. The arm 19 draws the link 20 forwardly to rock the shaft 23 and cause a finger or cam 29 80 thereon to interpose a dog or stop 30 in the path of the universal bar frame 10, to lock the escapement and thereby block the type bars and keys.

The swinging arm 19 is connected to the 85 link 20 by a pin 34, which is normally seated in a recess 35 in the link. A button 36 on a rock shaft 36^a, having a lifter 37 may lift the forward end of the link 20, to disengage the pin 34 from the seat 35, and bring a slot 90 39 in the link, (communicating with the seat 35,) in line with the pin, whereupon the finger 29 drops to idle position and the link 20 moves rearwardly the dog 30 returning to idle position to permit the type bars 95 to strike the platen. The dog 30 is guided in a socket 31 in the frame 9, and a shoulder 32 thereon, seating in a notch 33, supports the dog in normal idle position (Figs. 3 and 5). A returning spring 41 is preferably 100 employed for the dog. Further travel of the carriage in letter-spacing direction moves the tappet 12 away from the cam 13 whereupon the latter together with the arm 19, is returned to normal position by a 105 spring 42, the pin 34 reseating itself in the notch 35 in readiness to again project the dog 30 into the path of the universal bar, when the cam 13 is depressed by a second tappet 44 which engages the cam 13 after 110.

the carriage has been advanced a comparatively short distance, to lock the type bars and keys again.

Prior to the engagement of the tappet 5 with the cam 13, as aforesaid, the tappet strikes an incline 43 on the slide to rock the latter together with the rack 18 to swing the arm 19 forwardly a short distance. The throw of the arm draws the link forwardly 10 to draw a trip 24 (pivoted to the link at 24^a) along a cam 25 formed on a bell hammer 26 (pivoted at 27) to rock the hammer and then release it to strike a bell 23.

When the carriage returns to begin a new 15 line, the parts return to normal positions. The link 20, after the bell has been rung, does not again move endwise sufficiently to re-operate the bell striker, until the tappet or cam 12 runs down the cam 43, at the re- 20 turn stroke of the carriage.

Having thus described my invention, I claim:

1. In a typewriting machine, the combination with a key operated type, a part vibrated at each type stroke, and a traveling 25 carriage, of an arm rocked by the carriage, a rock shaft having a cam, a link connecting the arm and shaft, a bell, a clapper, a trip for the clapper moved by the link, and 30 a stop interposed by the cam in the path of the vibratory part.

2. In a typewriting machine, the combination with a key operated type, a part vibrated at each type stroke, and a traveling 35 carriage, of a cam adjustable along the path of the carriage, an arm rocked by the engagement of the carriage and cam, a rock shaft having a finger, a link connecting the arm and shaft, a bell, a clapper, a trip for 40 the clapper moved by the link, and a stop interposed by the finger in the path of the vibratory part.

3. In a typewriting machine, the combination with a key-operated type, a part vibrated at each type stroke, and a traveling carriage, of a combined bell-ringing and 45 line-locking cam in the path of the carriage, an arm rocked by the engagement of the carriage and cam, a rock shaft having a finger, a link connecting the arm and shaft, a stop interposed by the finger in the path 50 of the vibratory part, a bell, a hammer having a cam, and a trip on the link to rock the hammer.

4. In a typewriting machine, the combination with a key operated type, a part vibrated at each type stroke, and a traveling carriage, of an arm rocked by the carriage, a rock shaft having a finger, a link connected 60 with the shaft and having a recess communicating with a slot, a pin on the arm normally seated in the recess, to hold the link against movement independently of the arm, a stop thrust by the finger into the path of 65 the vibratory part, and a button to shift the

link on the pin to enter the latter in the slot and effect the return of the stop to idle position.

5. In a typewriting machine, the combination with a key-operated type, a part vibrated at each type stroke, and a traveling 70 carriage, of an arm rocked by the carriage, a rock shaft having a finger, a link connecting the arm and shaft and a stop mounted in the frame of the machine and controlled by the finger to arrest the vibratory 75 part.

6. In a typewriting machine, the combination with a key-operated type, a part vibrated at each type stroke, and a traveling 80 carriage, of an arm rocked by the carriage, a rock shaft having a finger, a stop adapted to be thrust by said finger into the path of the vibratory part, a link connected to the shaft and having a recess, a pin on the 85 arm normally seated in the recess to operate the link and lock the finger in use, and a button to cast off the link relative to the pin to enable the stop and finger to return to idle positions. 90

7. In a typewriting machine, the combination with a frame having a key-operated type, a carriage traveling on the frame, and a part vibrated at each type stroke, of an arm rocked by the carriage, a rock shaft 95 having a finger, a stop mounted in the frame of the machine and thrust into the path of the vibratory part by the finger, a link connected to the rock shaft and having a recess, a pin on the arm normally seated 100 in the recess to hold the stop in use, and a button to cast off the link relative to the pin to enable the finger and stop to return to their idle positions.

8. In a typewriting machine, the combination with a carriage, of a cam in the path of the carriage, an arm moved by the cam, a pin on said arm, a link having a recess to embrace said pin, a rock shaft moved by the link, a finger on the rock shaft, a universal bar vibrating with the keys of the typewriter, a stop moved by said finger into the path of the universal bar to lock the keys and the feed of the carriage, a signal operated by a trip on the link, and a button 110 to cast off the link from the pin to enable the stop to return to idle position. 115

9. In a typewriting machine, the combination of a cam operated by the carriage, a link moved by said cam, a trip moved by 120 the link, a bell clapper moved by the trip, a rock shaft moved by the link, a second cam operated by the carriage to move said rock shaft through said link to lock the machine, and means for simultaneously adjusting 125 both cams.

10. In a typewriting machine, the combination of a member moved by the carriage, a pin on said member, a bar having a slot, a recess extending from the slot to normally 130

embrace said pin to move said bar, an arm to lift said bar to release said pin from said recess, and a handle to move said arm.

11. In a typewriting machine, the combination with a key operated type, a part vibrated at each type stroke, and a carriage, of an arm moved by the carriage, a rock shaft having a finger, a link connecting the

arm and shaft, a bell rung by the link, and a stop in the frame of the machine controlled by the link to arrest the vibratory part. 10
